RACK FOR REFRIGERATOR CAR FLOORS
AND SIMILAR PURPOSESAlbert G. Dean, Narberth, Pa., assignor to The
Budd Company, Philadelphia, Pa., a corpora-
tion of Pennsylvania

Application November 25, 1947, Serial No. 788,055

8 Claims. (Cl. 105—375)

1

The invention relates to a rack consisting mainly of closely spaced slats interconnected by stringers. More specifically, the invention relates to a rack of the indicated type for use in refrigerator cars and other vehicles or for similar purposes.

Among the objects of the invention is a rack of the indicated type which is sturdy, durable, easy to clean, sanitary, light of weight, and easy and economical to manufacture in regard to its component parts as well as in regard to the assembly of the parts into the completed rack structure.

The aforesaid and other objects and advantages of the invention are achieved mainly by constructing the floor rack of sheet metal parts in the form of inverted channel section slats in combination with sheet metal stringers provided with flanged projections on their top margins for entering between and securement to the walls of the slats.

The aforesaid features as well as other features and details of the invention will be more fully and completely understood from the embodiment illustrated in the accompanying drawings and described hereinafter.

In the drawings:

Figure 1 is a fragmentary diagrammatic plan view of a railway car and of floor racks therein;

Figure 2 is a fragmentary section on a larger scale through several floor racks in and adjacent the region of a door opening, the section being taken along line 2—2 of Figure 1;

Figure 3 is a fragmentary plan view on the scale of Figure 2 showing the region surrounded by dot-and-dash line 3 in Figure 1 and looking in the direction of the arrows 3—3 of Figure 4;

Figure 4 is a fragmentary section and elevation along lines 4—4 of Figures 2 and 3;

Figure 5 is a fragmentary section along line 5—5 of Figure 2;

Figure 6 is a fragmentary section along line 6—6 of Figure 2;

Figure 7 is a section along line 7—7 of Figure 1 showing one floor rack unit in section folded against the side wall and other units resting on the floor;

Figure 8 is a fragmentary sectional view of the upper left-hand corner of Figure 6 but on a larger scale, the section being taken along line 8—8 of Figure 9;

Figure 9 is a fragmentary inside elevation of Figure 8;

Figure 10 is a section taken in the plane of line 10—10 of Figure 1 but showing two floor units in and adjacent the region of a door open-

2

ing folded upon each other and held together against one of the side walls;

Figure 11 is a plan view corresponding to Figure 1 of a modified embodiment; and

Figure 12 is a fragmentary section through one of the hinge supports taken along line 12—12 of Figure 11 on a larger scale.

Side walls 15, 16 and a floor 17 of a railway car are diagrammatically indicated in sections in the drawings. The side wall 16 is shown provided with a door opening 18. It is assumed that the illustrated cars are of the refrigerator type having ice or other refrigerating compartments in the end regions 19.

In the embodiment illustrated in Figures 1 to 10, the entire floor between the end compartments 19 is covered by a floor rack consisting, except in and adjacent the region of the door opening 18, of independent units 20. A pair of similar units 21 is arranged on both sides of the door opening 18 and each unit 21 is connected with one unit 22 extending over half the width of the door opening. The units 20, 21 and 22 are identical except for such differences as will be specifically pointed out hereinafter, so that the following general description applies to all three types of units.

Each of the rack units comprises a plurality of straight-sided inverted U-sections 23 having a bottom wall 24 and side walls 25. The channel sections or slats 23 are arranged parallel to and with close spacing between each other; the outsides of their bottom walls constituting the supporting surface for the rack.

The slats 23 are interconnected and supported by a plurality of stringers 26 having an upstanding web 27 and an angle section, bottom flange 28. The top of the web 26 is notched or recessed at 29 between the slats 23, leaving projecting portions 30 extending into the interior of the channel section slats 23. The upper margin of the projection 30 is provided with a lateral tongue or flange 31 resting against and secured to the inside of the bottom wall of the slats 23, preferably by electric spot welding. The margins of the recesses or notches 29 are reinforced by narrow flanges 32 which may extend in the opposite direction of the flanges 31 but in the same direction as the bottom flange 28. The stringers are provided along their end margins with a vertical flange 33 which rests against the inside of the side wall of the last slat of the unit and is secured to it, preferably by electric spot welding.

The slats are simple straight-sided profiles

which can easily be made on a roller or draw bench or on a power brake in mass production. Also, the stringers are of relatively simple construction, requiring only punching and pressing operations for the formation of the recesses 29 and their marginal flanges, whereas the other flanges may be formed on power brakes.

The slats and stringers can be easily, speedily and conveniently assembled by electric spot welding. The projecting portions 30 of the stringers insure the proper line-up and spacing of the slats during the assembly operation. In other words, the notches make the assembly self-gauging, thereby reducing tooling expense and improving production.

The slats 23 and stringers 26 consist preferably of a non-corrosive metal, for instance, austenitic stainless steel the strength of which has been increased by cold working. The accessories or hardware to be described later on consist preferably of the same material. The use of stainless steel has great advantages from the sanitation standpoint. Another advantage of the described and illustrated racks consists also therein that their weight is only about two-thirds of the weight of the hitherto customary wooden racks.

When in use, the rack units rest on the floor 17 by the flanges 28 of the stringers which support the slats 23 at a distance above the floor. Such arrangement of the slats is desirable for the disposal of water and other matter and for keeping the supporting surface dry and clean.

When not in use or when the underside of the racks and the floor surface 17 are to be cleaned, the rack units are folded up and held in upright position against the side walls 15 and 16. For this purpose, the racks are hinged by pins 34 to brackets 35 secured to the side walls by bolts 36. Each bracket 35 embraces both sides of the end of one of the slats 23. The pins 34 are supported in holes of corresponding size in the arms of the brackets 35 to which they are secured by arc tacks. The middle portions of the pins 34 extend through elongated holes 37 provided in the side walls 25 of the respective slat 23. The long axis of each hole 37 extends transversely to the bottom wall of the respective slat, that is, substantially vertically to the floor surface when the rack unit is in use. This elongated form of the holes insures the support of the floor rack units by the floor of the car to the exclusion of any support by the brackets 35 in the in-use position. On the other hand, when the rack unit is folded against the wall, it is supported by the brackets 35 and held entirely out of contact with the floor 17, thereby permitting unobstructed cleaning.

The rack units 22 in the door opening are hinged by brackets 38 and loose rivets 39 to the adjoining units 21. Note that the stringers of the units 21 and 22 are slightly offset with respect to each other and have their flanges 28 and 33 pointing in opposite directions; see Figures 2, 6 and 10.

After a pair of rack units 21 and 22 has been brought into upright position by swinging them about the hinge structures 34, 35 of the unit 21, the unit 22 can be folded against the unit 21 into the position illustrated in Figure 10 by swinging it about the axis of the pins 39.

Each of the units 20, 21, and 22 is provided with a hook 40, 41, respectively, adapted for engagement with one of the reinforced holes 42 of the side walls.

In the embodiment illustrated in Figures 11 and 12, a short rack 40 is arranged in the door opening 18 and hinged to an adjacent short rack

5 41. Another short rack 42 is arranged opposite the rack 40 and flanked by short racks 43. A short rack 43 is also arranged on the right side of the rack 40. The remainder of the length of the car between the racks 41, 43 and the end compartments 19 is covered by racks 44.

10 The construction of the racks 40 to 44 is very similar to the construction of the racks illustrated in Figures 1 to 10. The inverted channel section slats 45 are secured to stringers 46 of a construction substantially identical with the construction of the stringers 26. The difference resides in the oblique arrangement of the stringers as illustrated in Figure 11 and in the provision of triangular end pieces or slats 47 where the racks 40, 42 adjoin the racks 41, 43 and where the racks 44 adjoin the end compartments 19. These end triangles also are of inverted channel section and secured in the same manner to the stringers as described for the end slats shown in Figures 2 and 5.

15 The hinge support for the individual racks as shown in Figure 12 is slightly different from the hinge support of the first embodiment. The bracket 48 of each hinge support carries a pin 49 which passes through a loop 50 formed in a leaf 51, which latter is secured, preferably by electric spot welding, to the bottom wall of the adjoining slat 45. The arrangement of the loop 50 and its co-action with the pin 49 are the same as that of the elongated hole 37 and pin 34 illustrated in Figure 4 of the first embodiment.

20 While only two embodiments of the invention are illustrated and described, modifications and adaptations will easily occur to those skilled in the art. Protection is sought for the invention as covered by the spirit and language of the attached claims.

What is claimed is:

25 1. Floor rack for refrigerator cars and similar purposes comprising: a plurality of supporting stringers extending parallel to and being widely spaced from each other, and a plurality of floor slats closely spaced from each other in parallel relation and intersecting said stringers; said slats being in the form of inverted U-sections; said supporting stringers having upright webs with raised portions which are spaced from each other to fit into and supportingly engage the inside of said U-section slats, and arms bent off from the ends of said webs and overlappingly secured to the side walls of the slats along the margins of the rack.

30 2. Rack, especially for refrigerator car floors, comprising closely spaced slats of inverted channel sections and widely spaced stringers crossing said slats on the open side thereof, said stringers consisting of sheet metal profiles each having a web extending transversely to the plane of the bottom walls of said slats and being flanged along its margin adjoining the slats, said flanged margin having raised portions separated by recesses, said raised portions nesting in the interior of said channel sections while said recesses provide room for the side walls of the channels.

35 3. Rack, especially for refrigerator car floors, comprising closely spaced sheet metal slats of inverted channel sections and widely spaced stringers crossing said slats on the open side thereof, said stringers consisting of sheet metal profiles each having a web extending transversely to the plane of the bottom walls of said slats and being flanged along its margin adjoining the slats, the flanged margin having raised portions separated by recesses, said raised portions

nesting in the interior of said channel sections, and means interconnecting overlapping portions of said bottom walls of the slats and said flanged margin of said stringers.

4. In a rack for refrigerator car floors and similar purposes, closely spaced slats presenting the supporting surface of the rack, and widely spaced stringers crossing and interconnecting said slats, said slats consisting of sheet metal inverted channel sections each having a bottom wall, said stringers being in the form of angle sections each having one arm spaced from and parallel to the bottom walls of the slats to rest on the floor while the other arm extends toward the slats and has raised portions along its side nearer said slats, said portions being provided along their margins with flanges extending transversely to said other arm, said portions by their said flanges overlappingly engaging said bottom walls on the insides of said slats.

5. Rack, especially for refrigerator car floors, comprising closely spaced slats of inverted channel sections and widely spaced stringers crossing said slats on the open side thereof, said stringers consisting of sheet metal profiles each having a web extending transversely to the plane of the bottom walls of said slats and being flanged along its margin adjoining the slats, said margin having raised portions separated by recesses, the ends of said raised flanged portions nesting in the interior of said channel sections and being overlappingly secured to the inner surfaces of the bottom walls of said slats, said recesses providing room for the side walls of the channels.

6. Rack, especially for refrigerator car floors, comprising closely spaced slats of inverted channel sections and widely spaced stringers crossing said slats on the open side thereof, said stringers consisting of sheet metal profiles each having a web extending transversely to the plane of the bottom walls of said slats, the margins of said webs adjoining said slats being provided with recesses accommodating the side walls of said slats, said recesses having their margins reinforced by flanges extending in one direction from the respective web, the marginal portions between said recesses being provided with flanges extending in the opposite direction to said first-named flanges and being overlappingly secured to the bottom walls of said slats.

7. A metallic rack formed from stainless steel comprising a plurality of channel shaped members disposed in longitudinally spaced relation with respect to each other with the webs thereof coplanar and the side flanges thereof extending normal thereto, a plurality of supporting plates extending beneath said channel shaped members, said supporting plates being spaced along the under-surface of said channel shaped members in planes normal to the axes of said channel

shaped members, said plates each including curved recesses intermediate the side flanges of said channel shaped members with said recesses each reinforced with flanges extending normal to the plane of said supporting plate, tongues extending from said supporting plate in a direction opposite to the direction in which the aforesaid flanges extend and normal to the plane thereof and beneath the under-surface of the webs of said longitudinally extending channels and between the side flanges thereof, said supporting plate having end flanges thereon extending in a direction coincident with the direction of said first mentioned flanges and a rolled over terminating edge on said supporting plate forming a supporting foot therefor.

8. A metallic rack formed from stainless steel comprising a plurality of channel shaped members disposed in longitudinally spaced relation with respect to each other with the webs thereof coplanar and the side flanges thereof extending normal thereto, a plurality of supporting plates extending beneath said channel shaped members, said supporting plates being spaced along the under-surface of said channel shaped members in planes normal to the axes of said channel shaped members, said plates each including curved recesses intermediate the side flanges of said channel shaped members with said recesses each reinforced with flanges extending normal to the plane of said supporting plate, tongues extending from said supporting plate in a direction opposite to the direction in which the aforesaid flanges extend and normal to the plane thereof and beneath the under-surface of the webs of said longitudinally extending channels and between the side flanges thereof, said supporting plate having end flanges thereon extending in a direction coincident with the direction of said first mentioned flanges and a rolled over terminating edge on said supporting plate forming a supporting foot therefor, each supporting foot for each of the supporting plates connected with said channel shaped members extending in the same direction substantially parallel to each other.
